UNITED STATES PATENT OFFICE.

FREDERICK S. SHIRLEY, OF NEW BEDFORD, MASSACHUSETTS.

DESIGN FOR GLASSWARE.

SPECIFICATION forming part of Design No. 13,160, dated August 8, 1882.

Application filed July 6, 1882. Serial No. 66,046. Term of patent 7 years.

To all whom it may concern:

Be it known that I, FREDERICK S. SHIRLEY, a citizen of the United States, residing at New Bedford, in the county of Bristol and State of Massachusetts, have invented certain new and useful Improvements in Glassware Design; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

15 My invention relates to an improvement in designs for glass dishes; and it consists in making the body of the dish either round or oval and indenting it upon its sides with inwardly-recessed portions, as will be more fully 20 described hereinafter, whereby a beautiful and pleasing effect is produced.

The accompanying drawing is a plan view of a dish embodying my design.

25 A represents the dish, which may be either round, as here shown, or oval, and which has

a number of inwardly-recessed portions, B, formed in its sides. The sides of this dish are curved outwardly from the bottom, and are preferably ornamented upon their outer sides by means of grooves, which are cut in the 30 sides of the dish by means of a cutting tool, or any other suitable designs which will add beauty to the dish. The top edge of the dish may be also corrugated as shown. Where there is no foot to be used with the dish, any suitable design may be cut, engraved, or marked upon the bottom; but in case it is desired to have a foot upon the dish, so as to raise it upward and thus specially adapt it for berries, the design on its bottom can be dispensed with. 35

Having thus described my invention, I claim—

A design for a dish, substantially as shown and described.

In testimony whereof I affix my signature in 45 presence of two witnesses.

FREDK. S. SHIRLEY.
